COMBINED CHAIR AND WARDROBE

John S. Orsborn, Chicago, Ill.

Application March 14, 1955, Serial No. 35,020

Term of patent 14 years

(Cl. D15—1)

Fig. 2

Fig. 1

Fig. 3

Fig. 1 is a perspective view of a combined chair and wardrobe showing my new design;

Fig. 2 is a side elevational view thereof, some parts being broken away;

Fig. 3 is a fragmentary front elevation of an upper corner of the back of the chair;

Fig. 4 is a fragmentary perspective view illustrating the padded portion of the seat in raised position; and

Fig. 5 is a perspective view looking in the opposite direction from Fig. 1.

The dominant features of my design reside in the parts shown by solid lines on the drawings.

I claim:

The ornamental design for a combined chair and wardrobe, substantially as shown and described.
